UNITED STATES PATENT OFFICE.

KATHERINE E. BURNS, OF NEW YORK, N. Y., ASSIGNOR TO FRANKLIN SIMON & COMPANY, INC., OF NEW YORK, N. Y., A CORPORATION OF NEW YORK.

DESIGN FOR A DRESS.

Application filed August 1, 1928. Serial No. 27,663. Term of patent 3½ years.

To all whom it may concern:

Be it known that I, KATHERINE E. BURNS, a citizen of the United States, and a resident of the city of New York, in the county of New York, and State of New York, have invented the new, original, and ornamental Design for Dress, of which the following is a specification.

Reference is had to the accompanying drawing, forming part thereof, wherein

I claim:—

The ornamental design for a dress substantially as shown and described.

Signed at New York, in the county of New York, and State of New York, this 31st day of July, A. D. 1928.

KATHERINE E. BURNS.
